UNITED STATES PATENT OFFICE

PAUL A. BANCEL, OF MONTCLAIR, NEW JERSEY, ASSIGNOR TO INGERSOLL-RAND COMPANY, OF JERSEY CITY, NEW JERSEY, A CORPORATION OF NEW JERSEY

CONDENSER

Application filed September 18, 1929. Serial No. 393,435.

This invention relates to condensers, but more particularly to the water box of a condenser of the surface type.

It has been found that in certain condensers, as for instance, condensers of the horizontal type, the tubes leading from the uppermost regions of the water boxes are more readily subjected to corrosion than are those leading from lower levels. This is in 10 large part due to the froth created by the air which becomes separated from the cooling water and accumulates in the uppermost portion of the inlet water box. When carried into the tubes, the tubes become corroded and pitted, thus greatly shortening the life thereof and in some instances quickly reducing them to a condition which necessitates replacements after a comparatively short period of usage.

20 It is accordingly an object of the present invention to prevent the air entrained from separating from the water and to convey the air through the tubes in minute cells or bubbles. In this way the accumulation of 25 air and the consequent corrosive effect on the tubes will be eliminated.

Other objects will be in part obvious and in part pointed out hereinafter.

In the drawings illustrating the invention 20 and in which similar reference characters refer to similar parts,

Figure 1 is a longitudinal sectional elevation of a portion of a condenser constructed in accordance with the practice of the invention,

Figure 2 is a transverse view taken through Figure 1 on the line 2—2 looking in the direction indicated by the arrows, and

Figure 3 is a view similar to Figure 2 showing a modified form of the invention.

Referring to the drawings, A represents a casing of a condenser having an inlet opening B through which the steam may enter the casing A. A closure is provided 45 for the end of the casing A by a tube sheet C which supports one end of tubes D extending through the casing A and transversely of the steam flow.

The tube sheet C in the present instance 50 also serves as a closure for one side of a

water box E which may be secured to the casing A in any suitable manner. The water intended to be supplied to the cooling tubes D is introduced into the water box E through a pair of inlet openings F and G 55 preferably located near the bottom of the water box E and, which as is customary, are of smaller area than the water box E.

In accordance with the practice of the invention means are provided for assuring 60 the delivery of water to all the tubes at substantially the same velocity as that of the water flowing from the inlet openings F and G into the water box E. The means provided for this purpose comprises a pair 65 of baffles H and J spaced from and curved to substantially correspond to the curvature of the side wall of the water box E to form passages K and L which, in effect, are continuations of the inlet openings F and G 70 and extend upwardly through the water box E.

In cross-sectional area the passages K and L should preferably closely approach the areas of the inlet openings F and G so that 75 the initial velocity of the water may be substantially maintained during its upward course through the passages.

The baffles H and J may terminate a sufficient distance below the uppermost wall of 80 water box E so that the space between this wall and the ends of the baffles will readily permit the passage of the water reaching the upper ends of the passages K and L.

By suitably spacing the baffles H and J 85 a space or passage O will exist therebetween to guide the merging streams of water issuing from the passages K and L in a downwardly direction to supply the tubes D which communicate with the water box E at 90 points between the baffles H and J.

At the uppermost or inlet end of the passage O the baffles H and J may be suitably spaced to readily accommodate all the water flowing over the baffles. As the 95 water flows downwardly through the passage O, however, the volume thereof will be gradually reduced by the amount conveyed through the condenser by the tubes lying in the upper region of the condenser. The 100

baffles H and J may therefore be disposed in such wise that the area therebetween will be gradually reduced in a downwardly direction.

Obviously, in condensers in which the tubes are closely grouped it would be impractical to so form the baffles that no portion thereof overlapped the inlet opening of any of the tubes. In order therefore to enable baffles of practical forms to be used said baffles may be spaced a slight distance from the tube sheet so that water will not only flow over the upper ends of the baffles but will also readily flow between the side edges of the baffles and the tube sheet. This arrangement will assure an abundant supply of water to those tubes which may have their inlet opening in the same longitudinal planes as the baffles.

In the modified form of the invention shown in Figure 3, the water box E is provided with only one inlet opening F arranged in this instance at the extreme bottom of the water box. In the construction shown a pair of baffles P and Q form a continuation of the inlet opening F so that the water entering the inlet opening F will first flow upwardly through the passage R formed by the baffles P and Q to the extreme upper end of the water box E. There the water will be divided into two streams by the upper wall of the water box and will then flow downwardly between the baffles P and Q and the side walls of the water box. The baffles P and Q may be so arranged relatively to the side walls that the passages which they form will gradually diminish in area in the direction of the ends toward which the water flows.

By means of the present invention the velocity of the water flowing through the water box E may be prevented from falling below that of the entrance velocity of the water at any point throughout the water box. It is obvious therefore that any air entrained by the water will be prevented from separating from the water and from accumulating in any portion of the water box to create the undesirable condition which the present invention contemplates eliminating.

I claim:

1. A condenser, comprising a water box having an inlet opening, tubes communicating with the water box, and means in the water box forming a plurality of communicating passages therein to assure against a wide variation between the velocity of the water at the inlet opening and the velocity at which it flows through the water box.

2. A condenser, comprising a water box having an inlet opening, tubes communicating with the water box, and means in the water box forming communicating

passages therein to maintain the velocity of the water flowing through the water box at least equal to the velocity of the water flowing through the inlet opening.

3. A condenser, comprising a water box having an inlet opening, tubes communicating with the water box, and baffles in the water box arranged to form communicating passages in the water box to assure the delivery of water at substantially the same velocity to all the tubes.

4. A condenser, comprising a water box having an inlet opening, tubes communicating with the water box, and means dividing the water box into a plurality of communicating passages.

5. A condenser, comprising a water box having an inlet opening, tubes communicating with the water box, and baffles in the water box forming a series of communicating paths through the water box to assure a uniform velocity of the water flowing therethrough and thus assure against the separation of air from the water and the formation of air pockets in the water box.

6. A condenser, comprising a water box having an inlet opening of smaller area than the water box, tubes communicating with the water box, and means in the water box to form a continuation of the inlet opening through the water box and to prevent a reduction in the velocity of the water flowing through the water box below the entrance velocity of the water.

In testimony whereof I have signed this specification.
